UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

AXMINSTER TUBE FRAME.

Application filed March 6, 1922. Serial No. 541,336.

To all whom it may concern:

Be it known that I, EDGAR F. HATHAWAY, a citizen of the United States, and resident of Wellesley, in the county of Norfolk and State of Massachusetts, have invented certain new and useful Improvements in Axminster Tube Frames, of which the following is a specification.

This invention relates to tube frames such as are employed in supplying the tuft yarns in the operation of weaving Axminster carpets or other similar pile fabric; and is intended to remedy some of the practical objections incidental to the construction theretofore used in this art.

As is understood by those skilled in this art, the tube frames embrace generally speaking a longitudinal carrier-structure forming a support by which the series of individual tube-members, which form guides for controlling and delivering the yarn between the warp threads and the yarn-supplying spool, are supported and maintained in correct co-operative relationship. The tube frames carry the series of tuft yarns, each spool containing yarns of various colors in a predetermined arrangement or order. Each tube frame is carried into the machine usually by a pair of sprocket chains which serve to convey the individual tube frame into position to perform its operation of delivering the series of tuft tubes between the warp threads.

Inasmuch as it is vital to successful work that the individual tubes be not only accurately and uniformly spaced on the carrier-structure, but that the tube frame as a whole be moved into position to deliver the yarn with absolute precision and uniformity to enable the tuft tubes to pass between the proper warp threads, it is obvious that any construction which permits the position of successive tube frames or successive delivery movements of the same tube frame to vary in a lengthwise direction, tends to impair the accuracy and reliability of the mechanism.

As heretofore constructed the means for suspending the tube frame from its chain carrier or conveyor comprised two approximately vertical sheet metal arms, one of which was adapted to be sprung away from the other to allow the suspension arm or bracket to be inserted in the carrying link of the conveyor, while normally serving to

keep the bracket operatively engaged with a supporting link or member by a hook engagement. In practice however, such flexible sustaining or positioning arms easily become bent or displaced and this results in causing a sufficient longitudinal displacement of the position of the tube frame to interfere with the proper delivery of the tuft yarns between the appropriate warp threads. This necessitated careful and painstaking straightening or resetting of the suspension arms and has occasioned considerable practical difficulty in the operation of the tube frame.

The present invention overcomes this difficulty by providing a construction in which the two co-operating suspension members at each end of the tube frame are made rigid or inflexible, provision being made by a pivotal joint between them, and a yielding tension device to yieldingly maintain these two rigid suspension members at each end of the tube frame in operative position to securely attach the tube frame to its carrier in such manner that the tube frame is capable of quick attachment to and detachment from its carrier chain and at the same time preventing any longitudinal displacement of the tube frame due to distortion or bending of the suspension members.

Another feature of the invention consists in providing the main carrier bar of the tube frame with tube-positioning holding means for guiding and spacing the individual tubes so arranged as to firmly hold and reinforce the individual tubes in operative position on the carrier bar while permitting the quick detachment of the tubes therefrom.

These and other features of the invention will be particularly described in this specification and defined in the claims hereto annexed.

In the accompanying drawings I have illustrated a simple and convenient form of construction embodying the principles of this invention, in which—

Figure 1 is a plan view showing an end view of the tube frame as seen when placed in horizontal position.

Figure 2 is an end elevation of the structure shown in Figure 1.

Figure 3 is a detail view showing one of the suspension members detached from the other parts.

In the practice of the invention accord-

ing to the form illustrated in the drawings, the main carrier bar a is in the form of a hollow or tubular member of approximately a rectangular cross section. On its under side is secured a positioning and supporting member a^2 comprising substantially an angle iron whose projecting limb forms a continuation of the outer face of the carrier bar and terminates in an offset or angularly disposed flange a^3 which is provided with a series of transverse slots accurately dimensioned and spaced to receive the narrow forward or delivery ends b' of the individual tube-members b . The rear or intake ends of the tube-members into which the corresponding tuft yarns from the yarn spool m are inserted or threaded, have their under or back faces in plane surface contact with the outer face of the carrier bar a and the continuation of this face formed by the projecting limb of the angle bar a^2 . As will be understood by those skilled in the art, the forward, or in this case, delivery ends of the individual tubes are reduced in width as shown at b' to permit each delivery tube to pass between adjacent warp threads for the purpose of delivering the tuft yarn there-between. This reduced portion of each tube lies snugly within its appropriate slot in the ledge or flange a^3 , while the upper or rear end of the tube is clamped securely to the carrier bar a by means of any suitable connection, such as the detachable slotted clamping bar a' .

It will be seen that the extension and spacing support a^2 forms a continuation of the face of the carrier bar against which the flat back or under sides of the tubes are clamped and thus forms a material addition to the backing face against which the individual tubes are clamped for support, and in this way adds to the rigidity and strength of the tube-supporting connection.

The spool-supporting arm which forms one of the co-operating suspension members, comprises a fairly heavy rigid bracket c having a projecting boss c' of a form, in this case, rectangular, to fit snugly into the inside of the tubular carrier bar a . The boss is tapped on opposite sides, preferably the front and back sides, to receive fastening screws c^3 which pass through aligning perforations in the side walls of the tube so that the bracket is locked with absolute rigidity and firmness to the carrier bar. Arranging the fastening screws c^3 to pass through the front and back walls of the carrier bar affords easy access to the screws unobstructed by the overhead spool. The bracket c is provided with an additional boss c^5 formed with a central transverse bore at c^6 to afford a bearing for the journal of the rotatable yarn spool m . Above this

journal the bracket is extended or offset laterally for a short distance, and is then carried upward with its end coming to a wedge-shaped point c^7 to facilitate its entering the link in the carrier chain.

The offset portion of the bracket as shown at c^8 , is slotted to form a guide or keeper for the co-operating suspension member d , which is also sufficiently rigid to avoid bending under service strains, having at its upper end a link-engaging hook d^4 . The rigid hook d is provided at its lower end with an offset hook d' adapted to pass into a recess formed in the bracket c , in which it is pivotally secured on a pivot pin d^2 . In the countersunk recess c^9 on the outer face of the bracket is seated a compression spring of suitable size and tension to keep the hook d normally pressed into engagement against the upward extension c^7 of the bracket c .

This construction allows the suspension members to be separated in this case by the movement of the hook member d against the tension of its spring so as to permit the insertion of the upper end of the arm c into the supporting link, the hook being preferably beveled at its upper end so that the mere upward pressure against the link of the carrier chain, which is indicated in dotted lines in Figure 1, is sufficient to open the hook, the same being automatically closed by the spring d^3 when the suspension members have been passed a sufficient distance beyond the upper edge of the link.

The rigidity of the parts comprising the suspension structure does away entirely with their displacement or distortion longitudinally of the tube frame, which has been an incident to the use of the spring metal suspension members heretofore employed. As these suspension members are themselves inflexible or unbending, so far as ordinary service strains are concerned, they are incapable of causing lengthwise displacement of the tube frame from correct operative position. The rigid polygonal boss c' fitting snugly into the end of the tubular carrier bar affords a further element of rigidity to prevent displacement, while the long supporting surface afforded by the extension supporting member a^2 gives additional security against displacement of the tube-members when assembled operatively on the carrier-structure.

It may be observed that the construction by which the vertical suspension hangers are secured to the carrier bar affords an exceedingly strong and rigid joint yet without interfering with the detachability of these members. This is due principally to the fact that the laterally projecting attaching members of the hangers are so proportioned and arranged in relation to the walls of the carrier bar which they engage that

such interlocking engagement alone, even before the fastening screws are applied, acts to prevent either transverse or torsional displacement between the carrier bar and its hangers. Furthermore, the attaching members are so disposed on the inside faces of the hangers as to allow the end edges of the carrier bar to abut solidly against the inside faces of the hangers thus imparting additional solidity and stiffness to the frame. The pivotal axis of the hooked latch is protected by mounting it inside the receiving recess or transverse slot formed for that purpose in the suspension arm. Hence it will be seen that by the various features of construction shown and described the individual tuft tubes are firmly and rigidly attached by a detachable spacing connection with the carrier bar while the carrier bar and the hangers themselves form a supporting frame of the utmost rigidity and stiffness, and such frame is reliably and certainly engaged with the conveyor or carrier chain without any displacement or distortion of the co-acting parts.

The arrangement of the fastening screws c^3 which pass through the front and back walls of the hollow carrier bar into the inserted attaching wings of the end hangers is especially advantageous since it permits unobstructed access to the fastening screws without any interference with the yarn spool and without rendering it necessary to remove the yarn spool to tighten or remove these fastening screws.

What I claim is:

1. In a tube frame for tuft weaving, the combination of a longitudinal tube-supporting bar, vertical suspension arms rigidly secured to said bar to support said bar and a yarn spool in operative relationship, attaching members projecting laterally from the inside faces of the lower ends of said arms to form telescopic interlocking engagement with said bar, said attaching members being proportioned and arranged to prevent, by such engagement, angular and transverse displacement between the bar and said arms, and fastening means for preventing endwise displacement between the arms and the bar, substantially as described.

2. In a tube frame for tuft weaving, the combination with a longitudinal carrier bar, of spool-supporting hangers secured to the opposite ends of the bar said hangers and bar being constructed to have mutual interlocking engagement acting to prevent angular and transverse displacement between the hangers and the bar, and means for rigidly securing the bar to said hangers when arranged in such interlocking position, substantially as described.

3. In a tube frame for tuft weaving, the combination of a longitudinal carrier bar, vertical suspension arms having inwardly

projecting attaching members located at their lower ends, fastening means for rigidly securing the attaching members inside the ends of the tubular bar, said attaching members being formed to maintain holding engagement with the bottom and sides of the bar and thereby support lateral and torsional strains and relieve the fastening means of such strains, substantially as described.

4. In a tube frame for tuft weaving, the combination of a longitudinal hollow carrier bar, suspension arms secured across the ends of said bar and having attaching members projecting inwardly from their lower end portions inside the hollow ends of the bar in engagement with the front and rear side walls of the bar, and fastening devices inserted through said side walls of the bar and secured in said attaching members thereby affording access to the fastening devices unobstructed by the spool, substantially as described.

5. In a tube frame for tuft weaving, the combination with a longitudinal hollow carrier bar, of suspension hangers adapted to be secured to opposite ends of the tubular bar, the attaching members projecting inwardly from the lower end portions of said bar to engage interior walls thereof, said attaching members being located somewhat inside the lower end portions of the suspension hangers to allow the edges of the bar to abut firmly against the inside faces of the hangers, and means for rigidly securing the bar and the hangers together in such abutting relationship, substantially as described.

6. In a loom, a pattern chain, a supporting member, a spool bearing bracket secured thereto, a substantially rigid integral chain-engaging hook member connected to said bracket and having a hook at its free end, the other end of said hook member and said bracket being formed as parts of a pivotal connection between said hook member and bracket, and resilient means to force said hook yieldingly outward.

7. A suspension hanger for a tuft-tube frame embracing in its construction an inner vertical arm adapted to be rigidly secured to the end of the tuft-tube carrier bar, and having an upward chain-engaging extension outwardly offset from its lower bar-attaching portion, a chain, engaging rigid hook-arm pivotally mounted in the lower portion of the inner arm with its upper hooked end disposed inside said upward extension and normally spring pressed toward said extension in order to form therewith a suspension connection with a carrier chain that is releasable by inward pressure of transfer mechanism, substantially as described.

8. A suspension hanger for a tuft-tube frame embracing in its construction a spool bearing arm adapted to be rigidly secured

- to the end of a tuft tube carrier-bar, and comprising a lower bar-attaching portion and an upward chain-engaging extension outwardly offset therefrom, a rigid hook-
5 arm pivotally fulcrumed in a recess formed in said lower bar-attaching portion, and having at its upper end a chain-engaging hook and at its lower end an inwardly projecting member adapted to project into said 10 recess of the spool-carrying arm for its fulcrual support, substantially as described.
9. A suspension hanger for a tuft-tube frame embracing in its construction a spool-supporting arm adapted to be rigidly secured to a tuft-tube carrier bar comprising a lower bar-attaching portion and an upper chain-engaging member, a rigid chain-engaging hook arm having pivotal connection with said lower bar-attaching portion to be 15 pressed inwardly against the outer face of said spool-supporting arm by tube frame transfer mechanism, and a spring interposed between the two arms to press the hook yieldingly into engagement with a carrier chain, substantially as described.
- 20 10. A suspension hanger for a tuft-tube frame embracing in its construction a spool-supporting arm having an outwardly offset chain-engaging member at its upper end and having inwardly disposed bar-attaching and spool-bearing members the latter member located above said bar-attaching member and a rigid chain-engaging hook arm fulcrumed on the spool-supporting arm below the level of the spool bearing, and a spring for yieldingly pressing said hook arm outwardly away from the spool-bearing arm, substantially as described.
- 25 11. In a tube frame for tuft weaving the combination of a longitudinal carrier bar, an exterior longitudinal angle strip provided with a series of transverse tube-receiving and supporting slots rigidly secured against an external face of the carrier bar, and a 30 row of tuft tubes inserted in said slots to be held therein side by side with their back walls in engagement with a reinforcing face of the angle strip, substantially as described.
12. A tube frame for tuft weaving embracing a hollow longitudinal tube-carrying bar of substantially polygonal cross section combined with spool-supporting suspension hangers having attaching members inserted and rigidly secured inside the opposite ends 50 of the bar and an exteriorly disposed transversely slotted tube-receiving and supporting angle-bar rigidly secured to an exterior face of the hollow bar whereby the tuft tubes and the yarn supply spool may be held in positively fixed relationship, substantially as described.
13. In a tube frame for tuft weaving the combination of a tubular carrier-bar for supporting a row of tuft tubes side by side, 55 a tuft tube attaching and supporting element comprising an exterior longitudinal angle bar having an outwardly projecting slotted ledge forming positioning support around the tubular body of each tuft tube, an intermediate member affording a reinforcing backing engaging the back walls of the tuft tubes, and an attaching ledge arranged to be firmly secured to the bottom wall of the carrier bar, substantially as described.
- 70 14. In a tube frame for tuft weaving the combination of a hollow longitudinal carrier bar, a spool-bearing bracket provided with a chain-engaging portion, a spool-bearing portion and an attaching portion arranged to project inside the hollow bar in contact with the side and bottom walls of said bar, and means for securing said bracket rigidly in position, all parts of said bracket being formed of a single piece of metal, substantially as described.
- 80 In witness whereof, I have subscribed the above specification.
- EDGAR F. HATHAWAY.
